UNITED STATES PATENT OFFICE.

LEWIS E. MORRISON, OF NEWARK, NEW JERSEY, ASSIGNOR TO HUMANA COMPANY, A CORPORATION OF NEW JERSEY.

SAFETY-GUARD FOR PRINTING-MACHINES.

1,156,423.

Specification of Letters Patent.

Patented Oct. 12, 1915.

Application filed December 18, 1914. Serial No. 877,850.

To all whom it may concern:

Be it known that I, LEWIS E. MORRISON, a citizen of the United States of America, and a resident of Newark, Essex county, New Jersey, have invented certain new and useful Improvements in Safety-Guards for Printing-Machines, of which the following is a specification.

This invention relates to improvements in safety guards for printing machines and the object of the invention is to provide a safety guard particularly well adapted for use on a platen press, cutting, embossing or other machine operated on the principle of the well known Golding job press, in which the form member is stationary and the platen oscillates on a fixed center by means of a pair of toggles operated by a crank. The invention is, however, not limited in its use to a Golding jobber but is usable on machines for different purposes operated in a similar manner.

With the above and other objects in view the invention is embodied in a safety guard as set forth herein and as illustrated in the accompanying drawings in which—

Figure 1 is a side view of a machine representing diagrammatically a Golding platen press, or other machine operated on a like principle, and equipped with a safety guard embodying the principle of this invention; in this figure the press is shown open. Fig. 2 is a similar view showing the press closed. Fig. 3 is a view of the platen and the guard and Fig. 4 is a detail view showing a modification relating to the guard.

Referring to Figs. 1 and 2 the frame of the press or other machine is marked 5, and 6 is the stationary form member or jaw. 7 is the platen or movable jaw which swings or oscillates on a shaft 8 by means of a rocker arm 9. The platen is operated by means of the toggle links 10 and 11 which are actuated by a suitable member or link 12. Preferably, and as is well known, the link 12 is operated from the main shaft of the press by a crank, not shown. For the purposes of this disclosure the toggles 10 and 11 constitute a means for operating the platen. 13 is an arm connecting the platen to the toggle link 10. On each side of the press there is also an arm 14 which may be called an impression arm hereinafter, because it extends from the back impression shaft 50 to the front impression

shaft 15 on which latter the arm 13 and toggle link 10 are journaled. During the operation of the machine or press, the material to be acted upon, in this instance the paper to be printed, is placed and removed from the platen by the operator, whose hand or hands are frequently injured by being caught between the fixed and movable jaw or the form member and the platen. It is therefore the object of this invention to provide a safety guard to prevent such accident and so arranged that it may be secured to the machine without necessitating any changes in the construction thereof. Preferably the guard is in the form of a bar or member which is moved across the position of the operator's hand while feeding the material to the machine and whereby the operator's hand is forcibly prevented from being caught in the machine as the movable jaw closes upon the fixed jaw. In providing such a guard it is necessary or at least very desirable that it be so constructed and operated that the operator is allowed very nearly, or fully, as much time in which to feed the machine as he had without using the guard. Another consideration is that the guard must not interfere with the operation of the press, but is so arranged that only when the operator is slow in withdrawing his hand or careless does the guard move his hand away from danger.

The guard Fig. 3 comprises a cross bar 20 preferably a piece of tubing and two side bars. Each side bar comprises an outer tube 21, secured to the cross bar, and an inner tube 22 pivoted to the impression arms 14 aforesaid by means of a bracket 23 suitably secured to said arms 14, one on each side of the platen. The tube 22 slides within the tube 21 and a spring 24 is secured to the said tubes and tends to telescope the same in an obvious manner. The guard is secured to the platen by means of pivoted guides 25 through which the side bars 21 are adapted to slide. The elbows 26 which connect the cross bar 100 and the side bars form stops 27 adapted to abut the upper edges 28 of the guides 25 as hereinafter explained and similarly there may be provided a shoulder 29 on the tubes 22 adapted to abut the lower ends 30 of the tubes 21. The aforementioned stops may be formed or constructed in any suitable manner. The guides 25 are pivoted or swiveled

in brackets 31 secured to the corners of the platen as shown.

It will be seen that in the open position in Fig. 1 the guard is lowered with the platen and does not interfere with the feeding of the paper, also that the cross bar 20 is pulled down and kept down by the aforesaid springs 24, and the shoulder 27 abutting the edge 28 as above mentioned furnishes a convenient stop for the cross bar 20. As the platen moves toward the form it will be observed that the guard does not rise with respect to the platen until the lower edge 30 on the tube 21 abuts the shoulder 29 on the inner tube 22, as shown in dotted lines, which occurs at about the time the grippers 16 close and when the operator is through feeding the sheet and should withdraw his hand. As the platen now continues its movement and the impression arms 14 also swings upwardly, the guard is caused to rise above the platen until it reaches its highest position when the impression is on as shown in Fig. 2. During the latter part of the closing movement of the platen the cross bar describes a curve indicated at 35 which is directly across the position of the operator's hand and it follows that the hand will be forcibly moved away from the platen and accidents prevented. It also follows that on the opening movement of the platen, the guard is lowered in time so that when the grippers commence to open, the guard is out of the way and does not obstruct the subsequent manipulations of the stock. As a further precaution against accidents which might occur were the operator to attempt to seize a misplaced sheet or for any other reason attempt to thrust his hand forward below the cross bar and above the platen, there is secured to said cross bar a piece of canvas 36, the lower edge of which is secured to a roller or rod 37 secured to the back of the platen. It is sufficient to guard against accident that the canvas is secured so as to cover up the space between the platen and cross bar when the guard is raised, and the canvas will then bend into natural folds when the guard is down. It may, however, be desirable that the canvas be taut when the guard is up and for this purpose the roller 37 may be a spring shade roller as indicated at 38 in Fig. 3, so that the canvas will roll up as the guard is lowered. Or it may be sufficient to attach to the canvas one or more strips of elastic material 40 as in Fig. 4 and which insures that the canvas folds back of the platen when the guard is lowered. Other means for this purpose may be employed to prevent the canvas from folding in on the platen and thereby obstruct the manipulation of the material acted upon by the press, or a stiff guarding member may be used in place of the canvas.

65 The invention as illustrated and described

is not limited to the precise details disclosed, and I intend the appended claims to include such modifications as will embody the principles of the invention. The dimensions and shape of the guard securing means and of the guard itself may vary dependent upon the precise form of the machine upon which it is to be used.

With reference to the grippers 16 it will be understood that the movement of the guard is not timed exclusively with respect to said grippers, which are referred to only by way of illustration, but that the movement of the guard is timed with respect to the operation of the machine and with the views of giving perfect safety and not obstruct the operator's work. The operation of platen press grippers is so well known that no description or illustration thereof is necessary.

85 I claim:—

1. A guard for printing presses or similar machines having a movable platen or jaw and movable members coöperating therewith, said guard comprising a hand lifting cross bar and collapsible side bars carrying said cross bar and secured to said movable members, whereby said cross bar is moved across the position of the operator's hand as said platen closes.

95 2. A guard for printing presses or similar machines having a movable platen or jaw and movable members coöperating therewith, said guard comprising a hand lifting cross bar and collapsible side bars secured to said platen and carrying said cross bar and secured to said movable members, whereby said cross bar is moved across the position of the operator's hand as said platen closes.

100 3. The combination with a movable platen, of a guard mounted on said platen and adapted to be raised and lowered with respect to the same during the movement thereof, means for operating said guard, collapsible side bars for the latter and coöperating stops formed on said collapsible side bars for maintaining the guard in its relative position to the said platen for a predetermined length of time during the closing movement of the said platen.

105 4. The combination with a movable platen, of a guard mounted on said platen and adapted to be raised above the same during the closing movement thereof, collapsible side bars carrying said guard and provided with coöperating stops for preventing the guard from rising during the first part of the movement of the platen, said collapsible side bars serving as a means for operating said guard to reach its highest position 110 as the said platen completes its closing movement.

115 5. A guard for printing presses or similar machines having a movable platen or jaw and movable operating members therefor,

said guard comprising a hand lifting cross bar and collapsible side bars carrying said cross bar and pivoted to the said platen and the said movable operating members there-
5 for, whereby said cross bar is moved across the position of the operator's hand as said platen closes and a flexible guarding mem-
ber secured to said cross bar and said platen and adapted to cover the space between the

said two elements when the said cross bar is 10 lifted by the said collapsible side bars.

Signed at Newark, N. J. this 16th day of December, 1914.

LEWIS E. MORRISON.
